(57) **CLAIM**

The ornamental design for a wallet card multi-tool with mirror, as shown and described.

DESCRIPTION

FIG. 1 shows a top and side perspective view of a wallet card multi-tool with mirror.

FIG. 2 shows a bottom and reverse side perspective view thereof.

FIG. 3 shows a top plan view thereof.

FIG. 4 shows a bottom plan view thereof.

FIG. 5 shows a first side view thereof.

FIG. 6 shows a second side view thereof.

FIG. 7 shows a third side view thereof; and,

FIG. 8 shows a fourth side view thereof.

The broken lines depict unclaimed portions of the wallet card multi-tool with mirror only and form no part of the claimed design.

1 Claim, 5 Drawing Sheets

FIG. 3

FIG. 4

FIG. 5

FIG. 6

FIG. 7

FIG. 8
